UNITED STATES PATENT OFFICE

95,118

DESIGN FOR AN OIL DISPENSER

John F. Carter, Bryan, Ohio, assignor to The Aro Equipment Corporation, Bryan, Ohio, a corporation of Ohio

Application January 7, 1935, Serial No. 54,767

Term of patent 7 years

To all whom it may concern:

Be it known that I, John F. Carter, a citizen of the United States and a resident of Bryan, in the county of Williams and State of Ohio, have invented a new, original, and ornamental Design for an Oil Dispenser, of which the following is a specification, reference being had to the accompanying drawing, forming part thereof.

Figure 1 is a front elevation of an oil dispenser illustrating my design.

Figure 2 is a side elevation of the same.

Figure 3 is a horizontal sectional view on the line 3—3 of Figure 1, the dispenser being symmetrical about the center line.

I claim:

The ornamental design for an oil dispenser substantially as shown and described.

Des Moines, Iowa, December 20, 1934.

JOHN F. CARTER.
